UNITED STATES PATENT OFFICE.

EDWARD E. ALLEN, OF RUTLAND, AND PHILIP M. M. PHELPS, OF FAIR HAVEN,
VERMONT.

DESIGN FOR A COFFIN.

Application filed June 7, 1922. Serial No. 2,555. Term of patent 8½ years.

To all whom it may concern:

Be it known that we, EDWARD E. ALLEN and PHILIP M. M. PHELPS, citizens of the United States, residing at Rutland, county of Rutland, State of Vermont, and Fair Haven, county of Rutland, State of Vermont, respectively, have invented a new, original, and ornamental Design for Coffins, of which the following is a specification, reference being had to the accompanying drawing, forming a part thereof, in which—

Figure 1 is a top plan view of a coffin showing a new design,

Figure 2 is a side view of the same, and Figure 3 is an end view of the same.

We claim:—

The ornamental design for a coffin, as shown.

EDWARD E. ALLEN.
PHILIP M. M. PHELPS.
